DESIGN FOR AN ADVERTISING SIGN

John Kay, La Porte, Ind.

Application March 14, 1938, Serial No. 75,800

Term of patent 7 years

To all whom it may concern:

Be it known that I, John Kay, a citizen of the United States and a resident of La Porte, county of La Porte, and State of Indiana, have invented a new, original, and ornamental Design for an Advertising Sign, of which the following is a specification, reference being had to the accompanying drawing, forming a part thereof.

In the drawing:

Figure 1 is a front elevational view of a sign showing my new design.

Figure 2 is an end elevational view of the sign shown in Figure 1.

The horizontal lines on the frame merely designate visual contrast with the bordering surface, and the configuration of the base constitutes the dominant feature of my new design.

I claim:

The ornamental design for an advertising sign, substantially as shown and described.

JOHN KAY.
